(57) **CLAIM**

The ornamental design for a magnetic roofing hatchet, as shown and described.

DESCRIPTION

FIG. 1 is a perspective view of the magnetic roofing hatchet according to the invention;

FIG. 2 is a side view of the magnetic roofing hatchet as shown in FIG. 1;

FIG. 3 is a side view of the magnetic roofing hatchet as shown in FIG. 1, shown from the opposite side of that shown in FIG. 2;

FIG. 4 is a rear view of the magnetic roofing hatchet as shown in FIG. 1;

FIG. 5 is a front view of the magnetic roofing hatchet as shown in FIG. 1;

FIG. 6 is a top view of the magnetic roofing hatchet as shown in FIG. 1; and,

FIG. 7 is a bottom view of the magnetic roofing hatchet as shown in FIG. 1.

The broken lines depict portions of the magnetic roofing hammer in which the design is embodied but which are not considered part of the claimed design.

1 Claim, 6 Drawing Sheets
